ADJUSTABLE AND COLLAPSIBLE SUPPORT-
ING STRUCTURECharles T. Shoop, College Point, and Howard
Gohs, Elmhurst, N. Y.

Application November 1, 1940, Serial No. 363,858

4 Claims. (Cl. 311—95)

This invention relates generally to supports and refers more particularly to an improved supporting leg structure for tables or similar articles.

The invention broadly comprehends a supporting leg structure which is so constructed and arranged as to permit of the compact folding of the legs to occupy a minimum amount of space when not in use as well as the setting up of the legs to provide a support which may be varied in height and locked in its variously adjusted positions.

More particularly the invention comprehends a multiple cross leg support in which a plurality of pairs of pivotally connected cross legs are arranged to dispose said pairs respectively in planes at an angle to and intersecting each other for extending the legs to set up condition and for collapsing the same to a compact arrangement, together with a common means for locking the cross legs of said pairs in variously extended angular relations so as to vary the height of the support.

The invention has in view a table or similar support provided with an extensible and collapsible supporting leg structure consisting of a pair of cross legs pivotally connected together adjacent their longitudinal centers on a radial axis perpendicular to the direction of extension thereof and a second pair of cross legs similarly connected together adjacent their longitudinal centers on a radial axis perpendicular to the direction of extension thereof and intersecting the pivotal axis of the other pair and said pairs of cross legs being slidably and pivotally connected at their upper ends with the support for movement of the legs of each pair in parallel planes, the planes of movement of one pair of legs being at an angle to and intersecting the planes of movement of the other pair, and racks connected with the legs respectively and engaged by a pinion for synchronizing the movement of the legs to and from extended and collapsed condition with reference to the support.

With the above and other objects in view, the invention is set forth in greater detail in the following specification and illustrated in the accompanying drawings in which:

Fig. 1 is a bottom plan view of a table provided with an adjustable and collapsible supporting leg structure constructed in accordance with the invention and illustrating the same in collapsible condition.

Fig. 2 is a fragmentary sectional view taken approximately on the line 2—2 of Fig. 1.

Fig. 3 is a side view with the leg structure ex-

tended and locked in set up condition with parts broken away and shown in section to disclose the underlying structure.

Fig. 4 is an enlarged fragmentary plan view of the synchronizing and locking means for the legs.

Fig. 5 is a sectional plan view thereof.

Referring to the drawings by characters of reference, 10 designates a substantially rectangular table top having a depending marginal flange 11. The supporting leg structure includes two pairs of cross legs 12 and 13, and 14 and 15, the legs 12 and 13 being respectively pivoted on aligned trunnions 16 and 17 and the legs 14 and 15 respectively pivoted on aligned trunnions 18 and 19. The trunnions are disposed radially on intersecting axes perpendicular to the direction of opening and closing movement of the legs and are carried by a common central block 20. Under this arrangement the pair of cross legs 12 and 13 are disposed in parallel planes and the pair of cross legs 14 and 15 are disposed in parallel planes perpendicular to the planes of the legs 12 and 13 and intersect the same to permit of the extension of the legs to set up condition and the collapsing of the same to a compact arrangement where the legs may be nested within the flanged table top.

The upper end of each leg is connected for sliding and swinging movement with the underside of the table top by means of a transverse pin 21 engaging through a slot 22 in a bracket 23 depending from the underside of the table top 10 and preferably, as illustrated, the brackets 23 and the legs 12, 13, 14 and 15 are disposed diagonally of the table top. As illustrated, each of the legs is composed of a pair of spaced parallel straps 25 secured together at points intermediate the ends by spacer blocks 26 and at the lower ends by a foot piece 27 with the bolts or rivets 28 extending through the spacer blocks and foot pieces. The legs 12 and 13 adjacent their pivotal connection with the trunnions are oppositely notched as at 30 and 31, and the legs 14 and 15 are similarly notched as at 32 and 33 so that the legs when collapsed will permit of the nesting of the correspondingly notched portions thus allowing the legs to lie within a common plane. Thus when collapsed, the notched portions 30 of the legs 12 and 13 nest with the notched portions 32 of the legs 14 and 15, while the notched portions 31 of the legs 12 and 13 nest with the notched portions 33 of the legs 14 and 15.

In order to synchronize the movement of all of the cross legs, a rack bar 35 is pivotally con-

nected as at 36 with each cross leg at a corresponding distance from the trunnion, and the rack bars of one pair of cross legs intersect those of the other pair in overlapping relation and extend through guide slots 37 in a housing 38 with the teeth 39 of the several rack bars meshing with the teeth 40 of a common pinion 41 which is keyed to a shaft 42 journaled in the housing 38. The shaft 42 extends above the housing and has keyed thereto an exposed pinion 43 with the teeth of which a detent lever 44 is selectively engaged to lock the pinion 41 against turning movement. The detent lever is pivoted as at 45 on the housing 38 and is normally urged into engagement with the teeth by a spring 46 and is manually releasable by swinging of the lever against the action of the spring.

From the foregoing it will thus be seen that a supporting leg structure for tables or other articles has been devised in which the legs may not only be moved to and from a compact collapsible condition to an extended supporting position, but that the legs may be variously extended and locked in the variously extended positions to provide a support which is adjustable in height.

What is claimed is:

1. In a table, a top and an extensible and collapsible supporting leg structure including a pair of crossed legs pivotally connected together adjacent their longitudinal centers on a radial axis perpendicular to the direction of extension of the leg structure, a second pair of crossed legs pivotally connected together adjacent their longitudinal centers on a radial axis perpendicular to the direction of extension of the leg structure and intersecting the pivotal axes of the other pair of legs, interengageable means carried respectively by the underside of the top and the upper ends of the legs slidably and pivotally connecting the legs to the top for combined sliding and swinging movement of the upper ends of the legs of each pair towards and away from each other in parallel planes, the planes of movement of one pair of legs being at an angle to and intersecting the planes of movement of the other pairs of legs, racks pivotally connected to the legs respectively, and a pinion carried by said racks engaging the same for synchronizing the movement of the legs to and from extended and collapsed condition with reference to the top.

2. In a table, a top and an extensible and collapsible supporting leg structure including a pair of crossed legs pivotally connected together in spaced relation adjacent their longitudinal centers on a radial axis perpendicular to the direction of extension of the leg structure, a second pair of crossed legs pivotally connected together in spaced relation adjacent their longitudinal centers on a radial axis perpendicular to the direction of extension of the leg structure and intersecting the pivotal axes of the other pair of legs, means connecting the pairs of legs together at the intersection of the pivotal axes, interengageable means carried respectively by the under-

5 side of the top and the upper ends of the legs slidably and pivotally connecting the legs to the top for combined sliding and swinging movement of the upper ends of the legs of each pair towards and away from each other in parallel planes, the planes of movement of one pair of legs being at an angle to and intersecting the planes of movement of the other pairs of legs, racks pivotally connected to the legs respectively, and a pinion carried by said racks engaging the same for synchronizing the movement of the legs to and from extended and collapsed condition with reference to the top.

3. In a table, a top and an extensible and collapsible supporting leg structure including a pair of crossed legs pivotally connected together adjacent their longitudinal centers on a radial axis perpendicular to the direction of extension of the leg structure, a second pair of crossed legs pivotally connected together adjacent their longitudinal centers on a radial axis perpendicular to the direction of extension of the leg structure and intersecting the pivotal axes of the other pair of legs, interengageable means carried respectively by the underside of the top and the upper ends of the legs slidably and pivotally connecting the legs to the top for combined sliding and swinging movement of the upper ends of the legs of each pair towards and away from each other in parallel planes, the planes of movement of one pair of legs being at an angle to and intersecting the planes of movement of the other pairs of legs, racks pivotally connected to the legs respectively, a slotted housing through which the racks extend, a pinion journaled in said housing with which said racks engage for synchronizing the movement of the legs, an exposed pinion secured to the rack engaging pinion and a manually releasable spring pressed detent lever selectively engaged therewith for locking the legs in collapsed and variously extended positions to vary the height of the table.

4. In a table, a top and an extensible supporting leg structure therefor including a plurality of pairs of cross legs, means pivotally connecting the legs of each pair together intermediate their ends for movement in parallel planes, means slidably and pivotally connecting the upper ends of said legs with the underside of the table top, means of connection between the pairs of cross legs at their point of pivotal connection with each other for disposing the same for movement of one pair in planes perpendicular to the planes of movement of the other pair, a common means of connection between the several pairs of cross legs carried by said legs and located intermediate their pivotal connection with each other and their slideable and pivotal connections with the table top for synchronizing the movement thereof to and from collapsed and extended relation, and means for locking said legs in collapsed and various extended positions to vary the height of the table.
